UNITED STATES PATENT OFFICE.

THOMAS B. ATTERBURY, OF PITTSBURG, PENNSYLVANIA.

DESIGN FOR A BOTTLE OR JAR.

SPECIFICATION forming part of Design No. 18,218, dated April 3, 1888.

Application filed February 27, 1888. Serial No. 265,513. Term of patent 7 years.

To all whom it may concern:

Be it known that I, THOMAS B. ATTERBURY, a citizen of the United States, residing at Pittsburgh, in the county of Allegheny and State of Pennsylvania, have invented and produced a new and original Design for Bottles or Jars; and I do declare the following to be a full, clear, and exact description of the same, reference being had to the accompanying drawings, forming a part thereof.

My invention relates to designs for glass bottles or jars for holding mustard and other like substances; and it consists of a round body portion with a suitable base, the upper portion of the round body terminating in an annular ring or band, forming the base of the neck, and with ornamental leaves or scrolls extending from the base upward nearly to the annular ring.

My invention consists, further, of an ornamental cap or cover for the mouth of the bottle or jar.

Figure 1 is a view in perspective of the jar with the cap in an elevated position. Fig. 2 is a vertical sectional view of the jar with the cover in position.

A is the main body of the jar, and B the base. The body portion A is essentially round in general outline, the upper portion terminating in an annular ring or band, C.

D is the neck portion, which rises from the annular ring or band C and in a reverse curve to the main body.

E is an annular ring or projection formed on the upper end of the neck. The neck extends upward from the annular ring E to form the mouth of the jar.

H are the ornamental portions of jar, which consist of a series of leaves or scrolls in relief extending from the base B nearly up to the annular ring C, said ornaments being placed at intervals, so as not to mar the symmetry of the main body. The sides of the cap or cover F are fluted, as shown at I, said flutes extending from an annular bead, K, at the bottom of the cap up the plain band or portion L at the top of the cap. The top of the cap or cover F is provided with an elevated portion, b, formed in the center thereof, from which radiate a series of flutes or scallops, O.

I claim as my invention—

The design for a bottle or jar, composed of the round body portion A, having the ornaments H, annular ring C, reversely-curved neck D, and the ledge or projection E, substantially as shown and described.

In testimony whereof I affix my signature in presence of two witnesses.

THOMAS B. ATTERBURY.
